COASTER FOR BEVERAGE BOTTLES OR THE LIKE

Orville W. Thraikill, Wellington, Kans.

Application June 22, 1949, Serial No. 3,449

Term of patent 7 years

(Cl. D44—10)

To all whom it may concern:

Be it known that I, Orville W. Thraikill, a citizen of the United States and residing at Wellington, in the county of Sumner and State of Kansas, have invented a new, original, and ornamental Design for a Coaster for Beverage Bottles or the like, of which the following is a specification, reference being had to the accompanying drawing, forming part thereof.

Figure 1 is a view in side elevation of a coaster, embodying my new design, the opposite side being similar;

I claim:

The ornamental design for a coaster for beverage bottles or the like, substantially as shown.

ORVILLE W. THRAILKILL.
